TRIMMING-MACHINE.

1,393,656.

Specification of Letters Patent. Patented Oct. 11, 1921.

Application filed December 19, 1916. Serial No. 137,836.

To all whom it may concern:

Be it known that I, ERASTUS E. WINKLEY, a citizen of the United States, residing at Lynn, in the county of Essex and State of Massachusetts, have invented certain new and useful Improvements in Trimming-Machines; and I do hereby declare the following to be a full, clear, and exact description of the invention, such as will enable others skilled in the art to which it appertains to make and use the same.

One object of the present invention is to produce a machine for trimming off surplus material from a block or body of material such, for example, as the heel-pile or assemblage of lifts from which a heel is formed.

In the manufacture of heels in accordance with a system devised by the applicant, each heel is produced by cementing or otherwise securing together a stack of lifts or layers of suitable sheet-material, these lifts being rectangular or polygonal in form. After the heel-piles have been constructed they are brought approximately to the shape of the finished heel by means of a rounding operation wherein the surplus material is cut off so as to produce the characteristic rounded form of the heel. This operation is preferably performed by a machine having a rotary cutter, and if the original form of the heel-piles is rectangular, or departs, in any way, widely from the finished form, a considerable amount of work is imposed upon the cutter in removing the surplus material, when the rough heel-piles are submitted immediately to the rounding operation.

An object of the present invention is to produce a machine by which a preliminary trimming operation may be performed upon the heel-piles above referred to. In the illustrated machine this operation consists in cutting off the salient portions or corner elements of the heel-pile so as to approximate more nearly the rounded form of the heel. To this end it is proposed to employ a plurality of knives so mounted and actuated that they engage the heel-pile and bevel off two or more corner elements thereof, at the proper angles and to the proper depths.

In the method of manufacturing heels hereinbefore referred to, it is proposed to feed or advance the partly completed heels

from one to another of a series of machines, by which various operations are performed upon them, by means of a conveyer, which moves intermittently in a series of steps, thereby at each movement removing from each machine a heel which has been operated upon and bringing a fresh heel to the machine.

Another object of the present invention is to produce a machine which is adapted to constitute an element of a manufacturing system of this kind, and in which means are accordingly provided for removing heels or other articles singly from the conveyer, presenting them in proper position for the desired operation thereon, and then returning them after such operation, to the conveyer. To this end the invention comprises various devices hereinafter described, as they are defined in the annexed claims.

Other objects of the invention, and the features of construction by which they are attained, will be set forth hereinafter in connection with the description of the preferred embodiment of the invention.

In the accompanying drawings Figure 1 is a perspective view of a heel-pile which has been trimmed by the machine of the present invention. Fig. 2 is a side-elevation of a trimming-machine embodying the present invention. Fig. 3 is a front-elevation of the machine. Fig. 4 is a rear-elevation of the machine. Fig. 5 is a plan-view of the machine, with the upper parts broken away. Fig. 6 is a vertical section, approximately on the line 6—6 in Fig. 3. Figs. 7 and 8 are detail-views, in front-elevation and on a larger scale than the preceding figures, showing two different positions of a part of the mechanism for transferring the heel-piles to and from the trimming-knives; and Figs. 9 and 10 are detail-views, in side-elevation, showing parts of the same mechanism in two different positions.

The invention is illustrated as embodied in a machine with two trimming-knives 18 (Figs. 2 and 4) which cut downwardly toward a horizontal surface or cutting-table 20, upon which the heel-pile is supported in inverted position. The knives are adjustably fixed, at the proper angle, on a cutter-head 22, which is provided with lateral

flanges 24 by which it is supported in parallel guideways 26. These guideways are formed upon a stationary yoke 28, which is adjustably fixed on the frame of the machine.

The cutter-head is actuated by means comprising two gears 34, which are mounted on studs 30 on opposite sides of the frame of the machine. These gears are provided with 10 crank-pins 36, to which pitmen 38 are pivoted at their lower ends. The upper ends of the pitmen are connected by a beam 40, which is attached, by a pivot 42, to the cutter-head. Rotation of the pinions accordingly results in sliding movement of the cutter-head toward and from the cutting-table.

The gears 34 are rotated in unison by engagement with two pinions 44 fixed upon a transverse drive-shaft 46, which is journaled 20 in the frame of the machine. This drive-shaft is provided, at one end, with a gear 48 through which it may be connected with a source of power, and the drive-shaft is rotated constantly while the machine is in operation.

In order that the mechanism may be adjusted to bring the knives properly into engagement with the cutting-table after they have been sharpened, adjustable connections 30 are provided between the pitmen and the beam 40. For this purpose the upper portion of each pitman is screw-threaded, and is embraced by a threaded sleeve 50 which turns in a bearing in the corresponding end 35 of the beam 40. Each sleeve is provided with a bevel-pinion 54, and these pinions mesh with pinions 56 on the ends of a shaft 58 which is journaled in the beam 40. By the application of a wrench to a squared 40 portion 60 the shaft may be turned, thus causing the sleeves 50 to be rotated and to adjust the beam upwardly or downwardly upon the pitmen by action of the screw-threads. After the adjustment has been so effected, the parts may be locked in adjusted 45 position by means of lock-nuts 52 upon the pitmen, which are screwed into engagement with the ends of the sleeves 50.

The conveyer is shown as comprising a 50 series of links 64 (Figs. 3 and 5), each in the form of a flat metal plate 70 with lateral depending flanges. The links are connected together by pivot-rods 66 seated in perforations in the lateral flanges, and each rod is 55 provided, at its ends, with rollers 68. These rollers support that part of the chain which passes through the machine, by engagement with tracks 71 (Figs. 3 and 4) on the frame of the machine. Each chain-link is provided also with an upstanding flange 72 against which the breast of the heel-pile may be pressed to determine the position of the heel-pile upon the link.

No means are shown in the application

for actuating the conveyer-chain, as it may be understood that the machine is associated with one or more other machines provided with such means, an example of such machines being disclosed in Letters Patent of the United States No. 1,102,311, dated July 7, 1914, which shows a machine for performing the rounding operation herein referred to. It will be understood that after each intermittent movement through the space of one link, the chain comes to rest in the position shown in the drawings. It will also be understood that, through suitable positive driving-connections which need not be shown and described, the mechanism of the present machine is actuated in timed relation with the chain, so that its parts perform one cycle of operations for each feed-movement of the chain.

After each heel-pile has been brought to the machine by the advance of the conveyer, it is removed from the chain by a lateral movement which is produced by means of a pusher 74 (Figs. 3, 4 and 5). This pusher has the form of a curved arm fixed, at its lower end, upon a rock-shaft 76 which turns 85 in a bracket 78 on the frame of the machine. The rock-shaft is located directly beneath the conveyer, so that the upper extremity of the pusher moves in a short arc in an approximately horizontal direction.

After the heel-pile has been removed from the chain, by the pusher 74, to the surface of the cutting-table 20, it is advanced by a second pusher 80 (Figs. 5, 9 and 10) to bring it into position for engagement with the knives. The pusher 80 is carried by an arm 84, fixed to a shaft 86 which extends parallel with the length of the conveyer, but on the opposite side of the cutting-table. This shaft is mounted in bearings 88 and 90 100 on the frame of the machine, and it slides lengthwise in these bearings to cause the pusher 80 to advance the heel-pile on the cutting-table, while it also turns in the bearings so as to swing the pusher vertically into 105 and out of position to engage the heel-pile.

The advancing movement of the heel-pile under the influence of the pusher 80 is arrested and gaged by a stop-finger 92 (Figs. 5 and 6) which projects upwardly through an opening in the cutting-table, and the longitudinal position of the heel-pile is thus determined during the trimming operation. The heel-pile is positioned and retained laterally, during the trimming operation, by 115 means of two clamp-members 94 and 96 (Fig. 5) which engage its lateral surfaces. While the heel-pile is held by the clamp-members in engagement with the stop-finger 92, the cutter-head descends and the knives 120 bevel off the two corners of the heel-pile.

After the heel-pile has been trimmed, it is removed from the path of operation of the

knives by a further advancing movement, this movement being produced by a pusher 98 which also is fixed to and actuated by the shaft 86.

- 5 It is desirable that the two pieces of material removed from the heel-pile by the knives be discharged with certainty at a given point, and be thus prevented from clogging the mechanism of the machine. For 10 this purpose means are provided in the form of an arm 100 (Figs. 3 and 6), which is mounted to turn and slide upon a rod 102 fixed horizontally, at its rear end, in a bracket 106 on the frame of the machine. 15 This arm carries two adjustable parallel guard-plates 104 (Figs. 7 and 8). The movements of the shaft 86 are so timed that prior to the engagement of the work by the trimming-knives, the pusher 98 and the 20 guard-plates 104 are brought into co-operative relation with the heel-pile which is about to be trimmed, so that the several pieces are retained with the rough heel between the guard-plates until, by the succeeding 25 advancing movement of the parts, the severed pieces are brought to a position in which they may fall freely from the front of the cutting-table.

In the position attained by the rough heel 30 through the advancing movement just referred to, it is somewhat in advance of the vacant link of the conveyer-chain from which it was taken and to which it is to be returned, but upon the next retrograde movement of the shaft 86, the arm 100 is caused, by means which will be described, to participate in this movement through a short space, and a spring-finger 108 (Figs. 8 and 10) is fixed upon the arm 100 in position to engage 35 40 and push back the rough heel so as to bring it abreast of the link to which it is to be transferred.

The final return movement of the rough heel to the chain is produced by a pusher 110 45 (Figs. 3, 5 and 6) which is in the form of an arm fixed, at its lower end, upon a rock-shaft 112. The shaft 112 is mounted parallel with the rock-shaft 76, in a bracket 114 on the frame of the machine. The rock-shaft 112 is 50 so located that the arcuate movement of the upper end of the pusher 110 is approximately horizontal in direction.

To insure the correct positioning of the rough heel when returned to the chain, means 55 are provided for holding the heel firmly against the extremity of the pusher 110 during the operation of the latter. These means have the form of a plate 116 (Figs. 3 and 4) which is pivoted, at its upper end, to a yoke 60 118 supported by an arm 120 which overhangs the conveyer-chain. The plate is normally held in vertical position by a spring 122, but it yields and swings when the pusher moves the heel transversely, and the pressure

of the plate and of the pusher against the opposite lateral surfaces of the heel causes it to be alined correctly on the conveyer-link. The plate also presses against the top of the heel until it has been removed by the advance of the conveyer, and the resulting frictional 65 70 drag on the heel causes its breast-end to be pressed against the flange 72 on the chain-link.

The mechanism for actuating the pushers 74 and 110 comprises an arm 124 (Figs. 3 and 4) fixed to and projecting upwardly from the rock-shaft 76. This arm carries a roller 126 which engages a cam 128 on the power-shaft 46. The arm 124 is connected, by a link 130, with an arm 132 fixed on the rock-shaft 112, 75 80 so that both of the pushers are swung outwardly at the same time. The return-motion of the pushers is produced by a spring 134 attached to the pusher 110. The cycle of operations of the machine is such that both 85 the pushers act at the same time upon a heel-pile and a rough heel within their respective paths of motion.

The sliding and rocking movements of the shaft 86 are produced by cam-mechanism. 90 Two collars 136 (Figs. 5, 6, 9 and 10), fixed at one end of the shaft, loosely embrace a sleeve 138. This sleeve is provided with a stud 140, by which it is pivoted to a block 95 embraced by the forked upper end of a lever 142. The lever is pivoted, at 144, to a bracket 146 which constitutes a part of the frame of the machine. The bracket is provided with a second pivot 148, upon which a cam-lever 150 is mounted, and this lever is 100 provided with a roller 152 which engages a cam 154 on the power-shaft 46. The cam-lever is connected with the lever 142 by means of a link 156, so that the movements of the cam-lever are transmitted to the lever 105 142, thus producing longitudinal movements of the shaft 86. These movements are produced in one direction positively by the cam-mechanism, while the opposite movement is produced by a spring 160 attached to the 110 lever 142. In order that the amplitude of the movements may be adjusted in accordance with the size of the heel-piles which are being acted upon, the link 156 is pivoted by means of a stud which is adjustable within a 115 slot 158 in the cam-lever 150.

The rocking movements of the shaft 86 are produced by a segmental pinion 162 (Figs. 4 and 6), which is splined to the shaft, and is loosely embraced by the bifurcated bearing-member 88 so as to be restrained against axial movement. The pinion 162 cooperates with a rack-bar 164, which slides vertically in a guideway on the bearing-member 88. The rack-bar is pivoted, 120 125 at its lower end, to a link 166 which connects it with a cam-lever 168 mounted on the pivot-pin 148. This cam-lever carries a

roller 170 which engages a cam 172 on the power-shaft 46. The cam-mechanism acts to move the rack-bar positively in an upward direction, while its downward movements are produced by the action of gravity and of a spring 174 which is attached to the lower end of the rack-bar. The arrangement of the rack-bar and of the pinion 162 is such that the positive rocking movement imparted to the shaft 86 is that by which the pushers 80 and 98 are raised, while their descending movements are produced by the action of the spring 174. This arrangement has the valuable characteristic that it avoids breakage of the mechanism in case, by any accident, a heel-pile be positioned directly beneath one of the pushers at the time of the descending movement of the latter.

The arm 100 has rocking transverse movements simultaneous with those of the pushers supported by the shaft 86, but different in amplitude. These movements of the arm 100, however, are derived from the shaft 86. For this purpose a sleeve 176 (Figs. 7, 8, 9 and 10) is splined to the shaft, and is provided with an arm 178, of which the slotted end embraces a screw-stud 180 fixed in the arm 100. Owing to this arrangement, the rocking-movements of the shaft 86 are transmitted to the arm 100, as shown particularly in Figs. 7 and 8, so as to cause the guard-plates 104 to be raised and lowered together with the pushers 80 and 98.

The transverse movements of the arm 100 are produced through the agency of the sleeve 176. For this purpose the sleeve is provided with a flange 182 which engages a slot in the hub 184 of the arm. A tension-spring 186 connects the sleeve 176 with one of the collars 136 fixed on the shaft 86, and this spring tends to move the sleeve longitudinally on the shaft. Such movement is limited, however, by an arm 188 which projects from the sleeve and has a shouldered extremity arranged to coöperate with a collar 190 adjustably fixed on the shaft. To further control the movements of the sleeve 176, it is provided with a lug 192 in which an adjustable stop-screw 194 is fixed, this stop-screw being arranged to coöperate with a stationary stop-lug 196 fixed to the bearing-member 90 in which the shaft 86 moves.

The operation of the arrangement just described is such that during the first part of the longitudinal movement of the shaft 86, in the direction by which the pushers advance the heel-piles, the sleeve 176 is held stationary by the action of the spring 186, with the stop-screw 194 in engagement with the stop-lug 196. After a limited movement of the shaft 86, however, the collar 190 engages the end of the arm 188, so that thereafter the sleeve participates in the lengthwise movement of the shaft. Upon the return movement of the shaft, these operations

are reversed. The sleeve 176 and the arm 100 have, accordingly, a traversing movement of less amplitude than that of the parts supported and actuated directly by the shaft 86, this movement being only that which is necessary to permit the trimmed heel-pile or rough heel to be brought into position for the discharge of the several pieces as shown in Fig. 5, and then to be moved sufficiently in the opposite direction to aline it laterally with the conveyer-link to which it is to be transferred.

The clamping members 94 and 96 are supported and actuated in such a manner as to move toward each other in inclined paths of movement, whereby they have a tendency to push the heel-pile toward the stop-finger 92 and thus to insure its firm engagement therewith. The clamping-member 94 is integral with a yoke 198 (Figs. 4 and 5) which spans the conveyer-chain and extends beneath the latter. The lower end of the yoke is integral with an arm 200, which extends in a fore-and-aft direction. The ends of this arm are pivoted, respectively, to two radius-arms 202 and 204, of which the latter is mounted, at its inner end, on a stationary pivot 206, while the former is fixed to a vertical rock-shaft 208. The clamping-member 96 is supported in a somewhat similar manner, by two radius-arms 210 and 212, the arm 210 being mounted on a stationary pivot 214, while the arm 212 is fixed to a rock-shaft 216 which is parallel with the rock-shaft 208. The rock-shafts are connected for simultaneous opposite movement by two gears 218, and a spring 220, attached to the arm 212, acts in a direction to move the two clamping-members into engagement with the heel-pile. Movement of the clamping-members in the opposite direction is produced by cam-mechanism, and for this purpose an arm 222 (Figs. 5 and 6) is fixed to the rock-shaft 208 and provided with a roller 224 which engages a cam 226 on the power-shaft 46.

The stop-finger 92 is drawn downwardly, after it has performed its function, in order to permit the trimmed heel-pile to be advanced by the pusher 98, and this is accomplished by mechanism shown in Figs. 3 and 6. The finger is fixed to the inner end of a rod 228 which is fixed on an arm 230. This arm is mounted, at its upper end, upon a pivot 232 fixed in ears on the frame of the machine. A spring 234, attached to the stop-finger as shown in dotted lines in Fig. 6, tends to draw the finger upwardly into operative position. A bell-crank lever 236 is pivoted, at 238, to the frame of the machine, and the inner extremity 240 of this lever is in position to coöperate with a cam-surface on the periphery of the cam 226. This surface has a rise 242, which acts to swing the lever 236 so that a pin, fixed in the upper end thereof, engages the arm 230

and swings the arm outwardly, thereby depressing the stop-finger 92 below the cutting-bed at the proper time.

In order that the machine may be adjusted to operate upon heel-piles having different angles of pitch, the yoke 28 is so mounted as to be angularly adjustable. For this purpose, its ends are pivoted upon the studs 30 on which the gears 34 are journaled, and arms 244 (Fig. 4), which project upwardly from the bearings 32, are provided with clamp-bolts 246 which engage segmentally-slotted portions of the yoke (Fig. 6). Upon loosening the bolts, the yoke may be swung from vertical position through a limited angle, and since this angular adjustment is about the center of rotation of the gears 34, it does not interfere with the proper operation of the mechanism by which the cutter-head is actuated.

The operation of the machine as a whole is as follows: The conveyer-chain advances, in the direction of the arrow 248 in Fig. 5, through the space of one link, and thus brings a heel-pile to the position indicated at 250 in said figure. The pusher 74 then moves the heel transversely from the conveyer to the cutting-table. The shaft 86 is rocked, immediately afterward, in a direction to lower the pusher 80, which is, at this time, in the rear of the heel-pile. The shaft 86 is then advanced so as to bring the heel-pile beneath the trimming-knives and into engagement with the stop-finger 92. The clamping-members 94 and 96 then move into engagement with the heel-pile and hold it firmly between them and against the stop-finger. The shaft 86 then retracts, and after a short interval, which is allowed for a purpose which will be presently described, it is rocked so as to raise the pusher 98 clear of the clamped heel-pile, and the retreating movement is continued, thus bringing the guard-plates 104 into position on each side of the clamped heel-pile. While these movements are taking place, the cutter-head begins to descend, and the knives engage and trim the clamped heel-pile. At the same time the pusher 80 has been brought into position behind a second heel-pile, which has been transferred from the conveyer to the cutting-table, the conveyer having advanced through the space of one link during the advancing movement of the shaft 86 above described.

After trimming the heel-pile, the knives rise again, and the shaft 86 again advances, thus bringing a fresh heel-pile between the clamping-members. During the first part of this advance the arm 100 is stationary, but during the later part of the movement the arm advances, while the pusher 98 moves the trimmed heel-pile, or rough heel, together with the trimmings, to the front of the cutting-table, where the trimmings can

fall from the edge of the table. The shaft 86 then starts to retreat, and the first part of this movement causes the spring 108 to push the rough heel back from the edge of the table and into a position from which it can be transferred laterally to the conveyer. The shaft 86 then continues its retreating movement and is rocked, as before described, so as to raise the pushers 80 and 98 and the arm 100. While these parts are so raised, the pusher 110 transfers the rough heel to the conveyer, under the plate 116, at the same time that the pusher 24 is transferring a third heel-pile to the cutting-table.

It will be apparent that the machine so operates that each heel-pile, after its removal from the conveyer-link by which it is brought to the machine, is advanced through the machine alongside the conveyer and in the same direction as the intermittent movements of the latter, so that after the completion of the operation on the heel-pile it is returned again to the same link from which it was removed. This mode of operation is useful not only in a machine for performing the specific operation herein described, but also in other machines in which the articles operated upon are brought to and removed from the point of operation by an endless conveyer.

Throughout the specification and the claims, the term "conveyer", unless otherwise defined more specifically, is used generically to include any feeding means for advancing or conveying the article or articles, and is not in any sense restricted to define a feeding instrumentality which must necessarily support and carry the article or articles placed upon it.

While the present invention is particularly useful in connection with the operation of trimming heel-piles, it is not limited to such use, but may be used in the performance of various trimming operations. In general the invention is not limited to the embodiment thereof hereinbefore described and illustrated in the accompanying drawings, but may be embodied in various other forms within the scope of the following claims.

The nature and scope of the invention having been indicated, and its preferred embodiment having been specifically described, what is claimed as new is:—

1. A heel-trimming machine having, in combination, means for holding a heel-pile; and means for beveling off the adjacent rear corner elements of the heel-pile in angularly disposed planes that extend the entire height of the heel-pile and make obtuse angles with the planes of the upper or lower surfaces.

2. A heel-trimming machine having, in combination, means for holding a heel-pile; means for beveling off the adjacent rear

corner elements of the heel-pile in angularly disposed planes that extend the entire height of the heel-pile and make obtuse angles with the planes of the upper or lower surfaces; and means for adjusting the angularity of the planes on which the heel-pile is beveled.

3. A heel-trimming machine having, in combination, means for holding a heel-pile; cutting knives for beveling off the two adjacent rear corner elements of the pile by two separate cuts on planes that have obtuse angularity to the upper surface of the pile and cut all of the surfaces that bound each of said corner elements, and means for actuating said cutting knives.

4. A trimming machine having, in combination, means for holding a heel-pile; cutting means for beveling off the corner elements of said heel-pile; and means for ejecting the heel-pile and substituting another heel-pile.

5. The combination of cutting means for beveling off the corner elements of a heel-pile, and automatic means for feeding a succession of heel-piles to said cutting means.

6. A heel-machine having, in combination, a conveyer for feeding a succession of heel-piles, cutting means for beveling off the corner elements of the heel-pile; and means for successively transferring the heel-piles from said conveyer into position to be operated upon by the cutting means and for subsequently returning the heel-piles to the conveyer.

7. A heel-machine having, in combination, a conveyer movable progressively in one direction for advancing a succession of heel-piles, means for transferring each pile in turn from the conveyer and restoring it thereto at the same part thereof from which it is removed, and means for operating upon said pile while it is removed from the conveyer.

8. A trimming-machine having, in combination, a conveyer adapted to advance a succession of heel-piles; cutting-means adapted to bevel off the corner elements of a pile; and means for removing a pile from the conveyer, advancing it into position for operation by the cutting-means, and returning the pile laterally to the conveyer.

9. A trimming-machine having, in combination, a support; cutting-means for beveling off the two rear corner elements of a heel-pile upon the support; means engageable laterally with the pile, for centering it with respect to the cutting-means; and means operative upon a heel-pile upon the support for positioning the pile, in a longitudinal direction, with respect to the breast-end of the pile.

10. A trimming-machine having, in combination, cutting-means for beveling off the two rear corner elements of a heel-pile; a

support on which the pile may rest when operated on by the cutting-means; and means for centering the pile laterally and gaging its position longitudinally as it rests upon the support.

70

11. A trimming-machine having, in combination, cutting-means for beveling off the two rear corner elements of a heel-pile; a stop for engaging an end of the pile and fixing its position when operated upon by the cutting-means; and means for advancing the pile longitudinally and yieldingly into engagement with the stop.

12. The combination, with an intermittently movable conveyer arranged to advance a succession of articles, of instrumentalities, located adjacent the conveyer, for operating upon said articles; and mechanism operating, in timed relation with the movement of the conveyer, to remove successive articles from the conveyer, advance each such article, in the general direction of movement of the conveyer, to and past said instrumentalities, and return the article to the conveyer at the part thereof from which it was removed.

13. A trimming-machine having, in combination, a cutting-table; a cutter-head; a guideway for the cutter-head; and means including a crank-shaft for actuating the cutter-head; the guideway being angularly adjustable about an axis coincident with that of said crank-shaft.

14. A trimming-machine having, in combination, a cutting-table; a guideway pivotally mounted on an axis substantially coincident with the surface of the cutting-table; a cutter-head movable in the guideway toward and from said axis; pitmen connected to the cutter-head on opposite sides of the cutting-table; and cranks, for actuating the respective pitmen, rotatable about an axis coincident with the pivotal axis of the guideway.

15. A trimming-machine having, in combination, a cutting-table; a trimming-knife coöperating therewith; an end-stop for gaging the position of an article to be trimmed by said knife; two clamp-members arranged to engage and hold the article laterally; and means for moving the clamp-members toward each other in lines converging toward the end-stop, whereby the clamp-members are caused both to grip an article between them and to force it against the end-stop.

16. The combination, with a conveyer adapted to advance a succession of articles, of instrumentalities, located at the side of the conveyer, for operating on said articles; and mechanism operating to laterally transfer successive articles from the conveyer to said instrumentalities, and then to restore each article to the conveyer at the point thereof from which it was removed.

126

17. A trimming-machine having, in combination, cutting means for trimming excess material from a partly-manufactured heel; a support on which the heel may rest when operated on by the cutting-means; means for placing a heel upon said support; and other means for centering the heel laterally, and gaging its position longitudinally, on the support.
18. A trimming-machine having, in combination, a conveyer adapted to advance a succession of partly-manufactured heels; cutting-means for trimming surplus material from the heels; means for removing a heel from the conveyer, means for advancing it in the direction of movement of the conveyer into position to be operated upon by the cutting-means; and separate means for returning the heel to the conveyer.
19. A trimming-machine having, in combination, a cutting-table; means for clamping a partly-manufactured heel laterally to determine its position on the cutting-table; means engaging one end of the heel, to prevent endwise movement thereof; and a trimming-cutter operative upon the other end of the heel so held.
20. A trimming-machine having, in combination, a cutting-table; a slide-guide above the table; a cutter-head movable in the slide-guide; mechanism for reciprocating the cutter-head; heel-feeding means operating, in timed relation with said mechanism, to advance a partly-manufactured heel, upon the cutting-table, to a position beneath the slide-guide, prior to the descent of the cutter-head, and thereafter, by a further movement in the same direction, to remove the heel from beneath the slide-guide; and means operable upon the heel, when beneath the slide-guide, to gage and fix its position on the cutting-table.
21. The combination, with a conveyer for advancing a succession of articles, and means disposed adjacent the conveyer for operating upon said articles, of means operating in timed relation with said conveyer for removing successive articles from said conveyer, advancing said articles to and past said operating means in the general direction of movement of said conveyer, and returning said articles to said conveyer.
22. The combination, with a conveyer for advancing a succession of articles, and means disposed adjacent the conveyer for operating upon said articles, of means for removing successive articles from said conveyer, means for advancing said articles to and past said operating means in the general direction of said conveyer, and means acting concurrently with said removing means for returning said articles to said conveyer.
23. The combination, with a conveyer for advancing a succession of articles, and means disposed adjacent the conveyer for operating upon said articles, of means for removing successive articles from said conveyer, advancing said articles to and past said operating means in the general direction of said conveyer, and means for returning said articles to said conveyer.
24. A trimming-machine having, in combination, a cutting-table; trimming means cooperating therewith; a stop for gaging the position of an article to be acted upon; and means for engaging the sides of said article and rigidly clamping it in position against said stop during the trimming operation.
25. A heel-machine having, in combination, a conveyer for advancing a succession of heel-piles, means for laterally removing successive heel-piles therefrom and returning said heel-piles thereto at the points thereof from which they were removed.
26. A trimming-machine having, in combination, a cutting-table, a reciprocating cutter, means acting in timed relation to said reciprocating cutter for advancing partly manufactured heels successively along said cutting-table to position beneath said cutter prior to the cutting strokes thereof and thereafter by further movement in the same direction to remove the heels from said position; and means operable upon the heels beneath said cutter for gaging and fixing their position upon said cutting-table.
27. A trimming machine having, in combination, means for feeding a succession of heel-piles; cutting means for operating upon each heel-pile; a positive stop for definitely locating each heel-pile as it is fed to said cutting means, and means for withdrawing said positive stop to permit the further feeding of each heel-pile.
28. A heel-trimming machine having, in combination, means for holding a heel-pile, knives for cutting off on a bevel the rear corner elements thereof, and means for temporarily retaining in position the corner portions so cut and subsequently discharging them.
29. A heel-machine having, in combination, a conveyer movable progressively in one direction for advancing a succession of heel-piles, means for laterally removing each pile in turn to one side of the conveyer and for restoring it thereto at the same part thereof from which it is removed, and means disposed at the side of said conveyer for operating upon the pile while it is removed therefrom.
30. A heel-machine having, in combination, a conveyer movable progressively in one direction for advancing a succession of heel-piles, means for removing each pile in turn from the conveyer at one station, means for operating upon said pile while it is re-

moved, and means for restoring said pile to said conveyer at another station.

31. A heel-machine having, in combination, a conveyer movable progressively in one direction for advancing a succession of heel-piles, means for engaging and laterally moving each pile in turn from the conveyer at one station, means for operating upon said pile while it is removed, and other means for engaging and moving said pile back to said conveyer at another station.

32. The combination, with a progressively operating conveyer for advancing a succession of articles, of means disposed adjacent said conveyer for operating upon said articles in succession during the continued movement of the conveyer, and means for removing said articles in turn from the conveyer at one station and restoring them thereto after being operated upon at another station.

33. The combination, with a progressively operating conveyer for advancing a succession of articles, of means for removing articles in turn from said conveyer at one station, means for operating upon said articles during the continued movement of the conveyer, and means for returning said articles to said conveyer at another.

30 34. A heel-machine having, in combination, a conveyer for advancing a series of heel-piles, a supporting table adjacent said conveyer, means for transferring the heel-piles in turn from said conveyer to said table, means for operating upon the heel-piles, means for moving the heel-piles with respect to said table and into position to be operated upon, and means for returning the heel-piles to said conveyer.

40 35. A heel-machine having, in combination, a cutting table for supporting a heel-pile, means engaging the sides and one end of the heel-pile for clamping it firmly in position to be operated upon, and means for cutting the heel-pile.

45 36. The combination, with a conveyer for advancing a succession of articles, and means disposed adjacent the conveyer for operating upon said articles, of means for removing from the conveyer an article to be operated upon and concurrently restoring to the conveyer an article that has been operated upon.

37. The combination, with a progressively operated conveyer for advancing a succession of heel-piles, means for removing a heel-pile therefrom at one station and, after a period of continued operation of said conveyer, returning said heel-pile thereto at another station.

55 38. A heel-machine having, in combination, means for supporting a heel-pile, means for clamping the heel-pile firmly in position,

means for feeding a heel-pile into clamping position, a reciprocating knife having a rectilinear path of movement for operating upon the clamped heel-pile and means for adjusting the angular relation of the knife with respect to the heel-pile to vary the angularity of the path of movement and of the cut.

39. A heel-machine having, in combination, supporting means upon which a heel-pile rests, means for clamping the heel-pile firmly in position thereon, a reciprocating cutting knife for operating upon the heel-pile, and means for angularly adjusting the knife about an axis in the plane of the upper surface of the supporting means to vary the angularity of the cut.

40. A heel-machine having, in combination, stationary means for supporting a heel-pile, means for firmly clamping the heel-pile in position, a reciprocating knife for operating upon the heel-pile so clamped, and means for adjusting the angle of stroke of the knife to vary the angularity of the cut.

41. A heel-machine having, in combination, means for clamping a heel-pile firmly in position to be operated upon, a knife for operating upon the heel so clamped, means for reciprocating said knife, a guideway for said knife, and means for angularly adjusting said guideway to vary the angularity of cut of the knife.

42. A heel-machine having, in combination, means for successively feeding a plurality of heel-piles, a reciprocating knife disposed laterally of the path of feed for trimming said heel-piles, and means for transferring the heel-piles in turn from the path of feed into position to be operated upon by said knife.

43. A heel-machine having, in combination, means movable progressively in one direction for advancing a succession of heel-piles, means for laterally transferring each pile in turn from said advancing means and restoring it to the same portion thereof from which it is removed, and means for operating upon said pile while it is removed from said advancing means.

44. A heel-machine having, in combination, means for successively feeding a plurality of heel-piles, a reciprocating device disposed laterally of the path of feed for operating upon said heel-piles, means for engaging the sides of the heel-piles for positioning them to be operated upon, and means for laterally transferring the heel-piles in turn from the path of feed and presenting them to said positioning means by which they are positioned to be operated upon by said reciprocating device.

ERASTUS E. WINKLEY.

It is hereby certified that in Letters Patent No. 1,393,656, granted October 11, 1921, upon the application of Erastus E. Winkley, of Lynn, Massachusetts, for an improvement in "Trimming-Machines," errors appear in the printed specification requiring correction as follows: Page 4, line 92, for "iner" read *inner*; page 8, line 29, claim 33, after the word "another" insert the word *station*; and that the said Letters Patent should be read with these corrections therein that the same may conform to the record of the case in the Patent Office.

Signed and sealed this 15th day of November, A. D., 1921.

[SEAL.]

KARL FENNING,

Acting Commissioner of Patents.
